UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

REPRODUCING APPARATUS.

Application filed January 6, 1923. Serial No. 611,003.

This invention relates to a certain new and useful reproducing apparatus. More specifically as at present adapted, the reproducing apparatus is of a character utilizing a sound record such as the ordinary phonograph record.

The primary object of the invention is to effect a clear and distinct reproduction of sound waves that have been translated into a physical record, such as a phonograph record, such reproduction unaccompanied by the usual scratching or metallic sounds which are produced in the use of the present apparatus where a needle is pressed into a groove formed in the record and rides therein with very intimate contact.

Other objects and advantages relate to the details of the apparatus, all as will more fully appear from the following description taken in connection with the accompanying drawings, in which:

Figure 1 is a diagrammatic illustration of an apparatus of my invention.

Figure 2 outlines an ordinary phonograph disk record, no attempt being made to simulate the ordinary sound wave groove.

The apparatus as shown comprises a bulb or evacuated vessel —1— containing a filament —2—, a grid —3— and a plate —4—. These particular disclosures are illustrations of a heated electrode and two unheated electrodes. The filament may be heated in any suitable manner, as by means of a heating circuit containing a source of potential —5— and a rheostat —6—. The filament is connected in circuit with the plate, such circuit containing a source of potential —7— and a translating device such as telephone receivers —8—, which may, if desired be equipped with suitable amplifying devices as tapered horns and the like. The grid —3— is connected to a wire or conductor —9— that terminates in a needle —10—.

It is found that when this needle is held lightly in the sound record groove of the phonograph record —11— without any intimate or accurate contact with the said groove, that for some present unknown reason, a clear and distinct reproduction of the sound waves which were translated into the sound wave groove of the record is heard in the translating device, such as the telephone receivers —8—. The reasons for this reproduction and the reason for the generation of potential which is picked up by the needle

—10—, if any, or exactly what the operation is, is not known. It has, however, been repeatedly demonstrated that the result here described is obtained, and the recorded sound waves are reproduced in a clear and distinct manner without any scratching or metallic sounds, such as are caused by intimate contact of the needle with the record groove and my work up to the present time leads me to believe that friction electricity is generated by the relative movement of the sound record groove and the needle, which electricity is picked up from the non-conducting record and impressed upon the grid —3— thereby varying the current flowing in the filament plate circuit in accordance with the sound record groove.

Altho I have shown and described a specific adaptation of my invention, I do not desire to limit myself to the details of the same or to any specific apparatus, as I believe that I am the first to discover and produce an apparatus of this character.

I claim:

1. An apparatus for reproducing sound comprising an electron discharge device including a filament, a grid and a plate, a circuit connecting the filament and plate and including a source of potential and a translating device, and a needle adapted to ride in a groove in a sound record electrically connected to said grid without interposed capacity.

2. An apparatus for reproducing sound comprising an electron discharge device including a filament, a grid and a plate, a circuit connecting the filament and plate and including a source of potential and a translating device, and a needle adapted to ride in a groove in a sound record electrically connected to said grid without interposed capacity or potential.

3. The combination with a sound record and a conducting needle for contact therewith, of means for reproducing sound therefrom including an electron discharge device having a source of potential connected in circuit with the filament and plate of said device, and a conductor directly electrically connecting the said needle to the grid of said device without interposed capacity.

In witness whereof I have hereunto set my hand this 3rd day of January 1923.

THEODORE WILLARD CASE.
